Primary Examiner — Rosemary K Tarcza*Assistant Examiner* — Sanjeev Paul(74) *Attorney, Agent, or Firm* — Joseph M. Noto; Bond, Schoeneck & King PLLC(57) **CLAIM**

The ornamental design for a full immersive shield for smart glasses, as shown and described.

DESCRIPTION

FIG. 1 is a front elevational view of a full immersive shield for smart glasses for the new design;

FIG. 2 is a rear elevational view thereof;

FIG. 3 is a right side elevational view thereof;

FIG. 4 is a left side elevational view thereof;

FIG. 5 is a bottom plan view thereof;

FIG. 6 is a top plan view thereof;

FIG. 7 is a front quarter perspective view thereof;

FIG. 8 is a rear quarter perspective view thereof;

FIG. 9 is a left side elevational exploded view of a further embodiment of the design shown in FIG. 3;

FIG. 10 is a right side elevational exploded view of a further embodiment of the design shown in FIG. 4;

FIG. 11 is a bottom plan exploded view of a further embodiment of the design shown in FIG. 5;

FIG. 12 is a top plan exploded view of a further embodiment of the design shown in FIG. 6;

FIG. 13 is a front quarter perspective exploded view of a further embodiment of the design shown in FIG. 7; and,

FIG. 14 is a rear quarter perspective exploded view of a further embodiment of the design shown in FIG. 8.
